UNITED STATES PATENT OFFICE

VIGFUS S. HANSEN, OF LORAH, IOWA

SPRING TOOL

Application filed April 29, 1930. Serial No. 448,266.

The object of my invention is to provide a spring tool of strong, durable, simple and inexpensive construction, for conveniently spreading springs, such for instance as the 5 rear spring of the Model A Ford automobile, for releasing the spring shackles and removing the shackle bolts.

More particularly, it is my purpose to provide a spring tool of the kind mentioned, 10 having a cross bar peculiarly shaped and arranged for insertion at one end into the curl of the spring and having at its other end a beveled lever having an end adapted for insertion into the opposite curl of the spring 15 and being shaped and mounted for spreading and tensioning the spring and for permitting contraction of the spring without releasing the tool.

With these and other objects in view my 20 invention consists in the construction, arrangement and combination of the various parts of my device, whereby the objects contemplated are attained, as hereinafter more fully set forth, pointed out in my claims, and 25 illustrated in the accompanying drawing, in which:

Figure 1 shows a rear elevation of an automobile with my spring tool assembled in relation thereto for releasing the spring 30 shackles.

Figure 2 is a detailed, sectional view taken on the line 2—2 of Figure 1, parts being omitted.

Figure 3 is a view substantially similar to 35 that shown in Figure 2, illustrating the tool in another position of its adjustment.

Figure 4 is a perspective view of the lever forming part of the tool.

Figure 5 is a detailed, sectional view taken 40 on the line 5—5 of Figure 2; and

Figure 6 is an elevation of a spring having assembled therewith a modified form of my improved spring tool.

In some automobiles, for example the well-known Model A Ford, the rear part of the body is supported on a leaf spring having generally the shape of an inverted V.

The spring is supported at its ends on the chassis by means of shackles of well-known 50 construction. When the spring is under ten-

sion caused by the weight of the car body, it is difficult to take it out because the shackle bolts bind.

In the use of my improved spring tool the body of the car, indicated in the accompanying drawing by the reference numeral 10, is raised sufficiently in any suitable way, as for instance by means of the tackle indicated generally at 11.

This takes the weight off the spring 12 and, of course, in that case the spring tension will contract and move the ends thereof toward each other.

The spring 12 has at its opposite ends the curls or cylindrical portions 13 forming journals for the shackle bolts 14.

On the frame of the car are corresponding journals 15, Figures 1 and 2, receiving the opposite arm of the shackle bolt 14.

It will, of course, be understood that when 70 the spring 12 tends to contract, the arms of the shackle bolts bind tightly. It is quite difficult to remove them.

My improved tool for spreading the spring for conveniently removing the shackle bolts 75 comprises a cross-bar 16, the general shape of which is indicated in Figures 1 and 2.

The cross bar 16 has at its central portion a curved part 16a for clearing the differential casing.

At one end of the bar 16, being the left-hand end as shown in Figures 1, 2 and 3, the bar is tapered below as shown for instance in Figure 1 at 16b. The tapered portion is spread laterally as indicated for instance at 85 16c in Figure 3.

The tapered edge is arranged not quite at right angles to the axis of the bar. For instance, as shown in Figure 2, this tapered edge is inclined slightly so that the bar is 90 longest at what might be called the rear side. By rear side I mean the part which is rearwardly when the bar is installed for removing the spring.

The reason for this arrangement will be 95 made clear below.

A lever, indicated generally at A, is pivoted to the other end of the bar 16. The lever A may be made for instance from a single piece of bar folded over at the middle, as in- 100

dicated at 17 in Figure 4, to form a handle portion.

The material of the bar is then spread in both directions from the handle as indicated 5 at 18a in Figure 4. From the portions 18 and 18a the different stretches of bar material are curved to form U shaped members 19 and 19a, of which the arm nearest the handle 17 is shorter than the handle as 10 shown.

The lower member 19 is inclined upwardly and to the upper member and is welded thereto as at 20 to form a beveled edge 21 adapted to be received by the curl and the 15 body of the spring lever.

The edge 20 has near what may be called the front side of the lever A an inclined portion best illustrated perhaps in Figure 2 at 21a. The purpose of this inclined portion 20 will be later referred to.

The arms 19 and 19a are provided near the edge 21 with spaced pairs of holes 22 and 23. The pair of holes of each arm register with each other to receive pivot bolts or rivets or the like 24, extending through the end 25 of the bar 16, as shown for instances in Figures 3 and 5.

The members 19 and 19a of the lever A are sufficiently spread so that when the lever 30 is swung from one position to another, the bar 16 may freely clear between them.

The members 18 and 18a limit the swinging movement of the lever in one direction as shown in Figure 3.

Pivoted to the forward side of the bar 16 is a latch 25 which may be turned to position parallel with the bar where it does not interfere with the swinging movement of the lever, or may be turned to vertical position shown in Figures 1, 2 and 5, for instance, 40 where it serves as a stop for the lever A.

I will now describe the manner of using my improved tool and in connection with this description, refer to some of its advantages.

45 The car body having been raised, the tension is off the spring 12 and the ends of the spring 12 tend to move toward each other and are restrained by the shackles 14.

The nuts 28 may be removed from the ends 50 of the arms of the shackles, but the arms will still bind.

The workman swings the lever A to the dotted line position shown in Figure 2, and places the left hand end of the bar 16 adjacent 55 the inside of the curl 13 of the spring 12 as shown in dotted lines in Figure 2.

The edge 16c should be so arranged as to be about midway of the spring from side to side thereof. The edge 21 of the lever A 60 is then placed adjacent the inside of the curl of the other end of the spring until the corner of such edge engages the spring and the lever A is moved with a firm forward motion from the dotted line position shown in Figure 2 65 to the full line position shown in such figure.

Preferably the stop latch 25 is swung to vertical position before the adjustment of the spring tool so that when the lever A is moved to full line position it engages the stop latch.

It will be noted that the pivot 24 is arranged a little off the longitudinal center of the bar 16 so that when the lever A is in its full line position of Figure 2, the tension of the spring tends to swing the lever against the stop latch 25.

The adjustment of the lever will force the ends of the spring apart as shown in Figures 1 and 2. The shackles will then be loose and by slightly lifting the springs they may be easily removed.

The next step is to lift the body a little higher until the springs clear the chassis parts. This involves another problem.

On some cars there are projecting parts which interfere with such lifting of the body. It will be understood that the spring must be lifted straight upwardly because of other connections between the body and the chassis, not necessary to describe here.

In the Ford Model A for instance, the snubber attaching knobs 32 are above the shackle connections and project out over them.

When the spring is expanded, as shown in Figure 1 or as shown in Figure 2, the body and the spring can not be lifted upwardly 95 directly because these snubber attaching knobs stand in the way. So the workman turns the latch 25 from its position shown in Figure 5 to its position shown in Figure 3, where it is parallel with the bar 16 and swings 100 the lever A across the bar 16 from the position shown in Figure 2, to the position shown in Figure 3.

The spring, being under tension all the while, will of course contract, thus moving 105 its ends toward each other.

The movement of the lever A is limited by the engagement between members 18 and 18a with the bar 16 when the parts assume the position shown in Figure 3.

The tool will still be frictionally gripped by the spring, but the spring will have shortened as shown in Figure 3 until it can be lifted upwardly past the knobs 32.

The chassis may then be rolled out, or repairs may be made if desired.

When it is desire to replace the shackle bolts, parts are arranged with the rear axle in normal place located underneath the spring 12 and the body is lowered until the ends of the spring clear the knobs 32 and are below the level of the knobs. Then the operator reverses the operation of the tool, swinging the lever A from the position shown in Figure 3 to the position shown in Figure 2, whereupon the shackle bolts may be reinstalled.

It will be seen from the foregoing that the operation is simple and very fast.

It will be noted that I have provided a peculiar slant on the edge 16c so that when 135

the tool is adjusted from the position shown in Figure 2 to that shown in Figure 3 or vice versa, there will be at all times, as much bearing surface as possible at the edge 16c.

5 Similarly, I have provided the inclined portion 21a so that when the lever is moved to the position shown in Figure 3, that inclined portion rather than a sharp corner will bear against the spring.

10 It will be noted that I have provided the spaced holes 22 and 23 for the pivot bolt or rivet 24. This is for permitting the pivot to be located at different points for attaching the spring tool for use with different cars.

15 In Figure 6, I have shown a slightly modified form of my invention in which I have provided a single cross bar 36, the ends of which are beveled at 37.

The bar 36 has the central raised portion 20 36a, similar to the portion 16a. In using the bar 36, the bar is placed between the spring curls, while the load is imposed on the spring and then when the body is raised the bar is held in position and the spring will naturally 25 contract to grip the bar. When the body is raised far enough, the shackle bolts will be loose and can be readily removed.

From the foregoing it will be obvious that 30 some changes may be made in the construction and arrangement of details and parts of my device, without departing from the essential spirit and purpose of my invention, and that it is my purpose to cover by my 35 claims, any modified forms of structure or use of mechanical equivalents which may be reasonably included within their scope.

I claim as my invention:—

1. For use with a bowed spring having 40 eyes at its ends, a spring tool comprising a pair of toggle levers pivoted together to assume an initial contracted position and to swing in one direction to an extended position and thereafter to a partially contracted position and means for normally stopping said levers in said partially contracted position.

2. For use with a bowed spring having eyes at its ends, a spring tool comprising a pair of 50 toggle levers pivoted together to assume an initial contracted position and to swing in one direction to an extended position and thereafter to a partially contracted position, means for normally stopping said levers in said partially contracted position and selectively operable means for stopping said levers in said extended position.

3. For use with a bowed spring having eyes at its ends, a spring tool comprising a pair of 60 toggle levers pivoted together to assume an initial contracted position and to swing in one direction to an extended position and thereafter to a partially contracted position, one of said levers being split to straddle the other and having converging ends to normally engage the other lever and thereby act as

stop means for the levers in said partially contracted position.

4. For use with a bowed spring having eyes at its ends, a spring tool comprising a pair of toggle levers pivoted together to assume an initial contracted position and to swing in one direction to an extended position and thereafter to a partially contracted position, one of said levers being split to straddle the other and having converging ends to normally engage the other lever and thereby act as stop means for the levers in said partially contracted position and selectively operable means for stopping said levers in said extended position. 70

5. For use with a bowed spring having eyes at its ends, a spring tool comprising a pair of toggle levers pivoted together to assume an initial contracted position and to swing in one direction to an extended position and thereafter to a partially contracted position, means for normally stopping said levers in said partially contracted position and a turn button on one lever to selectively stop the other lever when the levers are in said extended position and when the turn button is in one of its positions and for allowing the normal stop means to operate when the button is in another of its positions. 80

6. For use with a bowed spring having eyes at its ends, a spring comprising a pair of toggle levers pivoted together to assume an initial contracted position and to swing in one direction to an extended position and thereafter to a partially contracted position and means for normally stopping said levers in said partially contracted position, the ends of said levers which engage said eyes of said spring being rounded to allow rolling action 100 of said ends against said eyes during movement of the tool to its various positions. 105
